Patented November 8, 1904.

UNITED STATES PATENT OFFICE.

SIGMUND STERNAU AND LIONEL STRASSBURGER, OF NEW YORK, AND JOHN P. STEPPE, OF BROOKLYN, NEW YORK, ASSIGNORS TO S. STERNAU & COMPANY, OF NEW YORK, N. Y., A COPARTNERSHIP.

DESIGN FOR AN ALCOHOL-FLAGON.

SPECIFICATION forming part of Design No. 37,211, dated November 8, 1904.

Application filed September 28, 1904. Serial No. 226,374. Term of patent 7 years.

To all whom it may concern:

Be it known that we, SIGMUND STERNAU, of 325 Central Park west, and LIONEL STRASSBURGER, of 1279 Madison avenue, New York city, and JOHN P. STEPPE, of 759 Putnum avenue, Brooklyn, New York, have invented a new, original, and ornamental Design for an Alcohol-Flagon, of which the following is a specification, reference being had to the accompanying drawings, forming part thereof, and in which—

Figure 1 is a side elevation, and Fig. 2 is a

plan view, of an alcohol-flagon, showing our new design.

What we claim as new, and desire to secure by Letters Patent, is—

The ornamental design for an alcohol-flagon, as herein shown.

SIGMUND STERNAU.
LIONEL STRASSBURGER.
JNO. P. STEPPE.
